UNITED STATES PATENT OFFICE.

EDWARD GREGORY, OF GROVE CITY, PENNSYLVANIA.

COMBINED TOOL AND BUSHING FOR PNEUMATIC HAMMERS.

1,160,507.

Specification of Letters Patent.

Patented Nov. 16, 1915.

Application filed June 15, 1914. Serial No. 845,136.

To all whom it may concern:

Be it known that I, EDWARD GREGORY, a citizen of the United States, residing at Grove City, in the county of Mercer and State of Pennsylvania, have invented certain new and useful Improvements in Combined Tools and Bushings for Pneumatic Hammers, of which the following is a specification.

10 This invention relates to new and useful improvements in bushings adapted to cooperate with a tool of similar formation to that of the bore of such bushings and this combination is especially adapted to be used 15 in connection with pneumatic hammers or the like.

An object of this invention is the provision of a bushing so constructed as to strengthen the shank portion of the tool operating therein, thereby lengthening the life 20 of the same.

With the above and other objects in view this invention resides in the novel features of construction, formations, combinations 25 and arrangements of parts to be hereinafter more fully described, claimed and illustrated in the accompanying drawings in which:—

Figure 1, is a longitudinal sectional view of my bushing with tool applied, and with 30 same removed from hammer cylinder, Fig. 2, is a rear elevation of the bushing with tool in position, Fig. 3, is a front elevation of the bushing removed, Fig. 4, is a longitudinal sectional view of the same, and, Fig. 35 5, is a side elevation of the tool removed.

Referring to the accompanying drawings by similar characters of reference throughout, the numeral 10 designates my improved bushing in general, which is employed at 40 the end of the hammer cylinder, not illustrated in the accompanying drawings, and secured thereto by the customary means, but as shown by Fig. 1, of the accompanying drawings, I have the bushing applied to a 45 chisel or similar tool A. This bushing 10 is of the ordinary construction having the customary body portion 11 with a flange 12 formed therefrom at its outer end, while the bore 13 in which operates the tool A is of a 50 novel construction and it is in this bore and coöperating parts of the tool A, that I base my claim.

With reference to Fig. 4, of the accompanying drawings it will be manifest that 55 I have provided a tapering cylindrical bore 14 within the said bushing 10 which extends

over the outer end of the same inwardly to the intermediate portion of the body portion 11, at which point this bore terminates into a seat 15, which has extending therefrom a 60 reduced octagonal bore 16 which extends therethrough the remaining length of the body portion 11 and which is for the reception of the octagonal shank B of the chisel or tool A. This chisel or tool A is formed 65 with a corresponding shape to that of the entire bore 13 of the bushing 10 so that the same will readily operate therein and as clearly illustrated by Fig. 5, of the accompanying drawings, it will be readily seen 70 that this chisel or tool A has the customary blade end C which terminates into a tapering cylindrical body portion D corresponding in shape to that of the tapering bore 14 of the bushing 10. This body portion D 75 terminates into a shoulder E which seats itself into the seat 15 of the bore 14 when the tool is in operation, while extending from this shoulder E is the octagonal shank B which operates within the octagonal bore 80 16, of the said bushing, and it is upon the extreme end F of this shank B that the plunger of the pneumatic hammer or like delivers its repeated blows.

In view of the above it will be readily 85 understood that I have provided a bushing and tool that will prove far superior in strength to that of such tools in use at the present time, as the tapering bore 14 of my bushing coöperating with the corresponding 90 body portion D of the tool A when in use will have the greatest tendency to strengthen the blade end C of the said tool thereby producing a means whereby the breaking of numerous such blades will be greatly reduced. 95 I have also provided the octagonal bore 16 of the bushing for the purpose of reducing the wear and tear upon the shank portion of such tools, as it is a well known fact that cylindrical shank portions or the like produced upon such tools will eventually wear out of shape, their sides becoming somewhat flattened after a short period of constant use, but by providing a tool with my octagonal shank B to coöperate with a similar 100 105 bore, a means is provided whereby the wear and tear is equally distributed on all sides of such shank portions, thus it will be readily understood that I have provided a means whereby the shank of such tools is 110 greatly preserved and with a bushing and tool constructed as herewith described and

illustrated, it will be manifest that the life of such tools will be greatly lengthened and that furthermore such a combination will prove far superior to those in use at the 5 present time.

It should be understood however that while this combination of tool and bushing are especially adapted for pneumatic tool use, the same combination may be used in 10 connection with various devices operating various tools in such bushing. It should further be understood in this connection that various minor changes in the details of construction may be resorted to within the 15 scope of the appended claim, without departing from or sacrificing any of the advantages of this invention.

From the foregoing disclosure it will be manifest that a bushing for pneumatic hammers or the like of the character described is 20 provided, which will coöperate with a suitable tool and thus fulfil all of the necessary requirements of such a device.

Having thus fully described this invention what I claim as new and desire to protect by Letters Patent is:—

The combination with a tool having a tapering cylindrical body terminating in a polygonal shank forming a shoulder therebetween of a bushing having a tapering cylindrical bore and a polygonal bore extending therefrom with a seat therebetween for the reception of the shank and engagement with the shoulder and tapered body of the tool and said polygonal bore being open at the outer terminal thereof to permit the polygonal shank to receive the necessary repeated blows from the pneumatic plunger or the like.

In testimony whereof I affix my signature 40 in presence of two witnesses.

EDWARD GREGORY.
